Primary Examiner — Katie Jane Stofko(74) *Attorney, Agent, or Firm* — Arent Fox LLP**CLAIM**

The ornamental design for a confectionery bar, as shown and described.

DESCRIPTION

FIG. 1 is a top, left perspective view of a first embodiment of a confectionery bar;

FIG. 2 is a right side elevational view of the confectionery bar of FIG. 1;

FIG. 3 is a left side elevational view of the confectionery bar of FIG. 1;

FIG. 4 is a front elevational view of the confectionery bar of FIG. 1;

FIG. 5 is a rear elevational view of the confectionery bar of FIG. 1;

FIG. 6 is a top plan view of the confectionery bar of FIG. 1;

FIG. 7 is a bottom plan view of the confectionery bar of FIG. 1;

FIG. 8 is a top, left perspective view of a second embodiment of a confectionery bar;

FIG. 9 is a right side elevational view of the confectionery bar of FIG. 8;

FIG. 10 is a left side elevational view of the confectionery bar of FIG. 8;

FIG. 11 is a front elevational view of the confectionery bar of FIG. 8;

(Continued)

FIG. 12 is a rear elevational view of the confectionery bar of FIG. 8;
 FIG. 13 is a top plan view of the confectionery bar of FIG. 8;
 FIG. 14 is a bottom plan view of the confectionery bar of FIG. 8;
 FIG. 15 is a top, left perspective view of a third embodiment of a confectionery bar;
 FIG. 16 is a right side elevational view of the confectionery bar of FIG. 15;
 FIG. 17 is a left side elevational view of the confectionery bar of FIG. 15;
 FIG. 18 is a front elevational view of the confectionery bar of FIG. 15;
 FIG. 19 is a rear elevational view of the confectionery bar of FIG. 15;
 FIG. 20 is a top plan view of the confectionery bar of FIG. 15; and,
 FIG. 21 is a bottom plan view of the confectionery bar of FIG. 15.
